APPARATUS FOR HEATING, POWER, AND
REFRIGERATION PURPOSES

August Schwarz, Chicago, Ill.

Application March 2, 1934, Serial No. 713,685

27 Claims. (Cl. 257—6)

One object of my invention is the provision of apparatus especially designed for quickly and efficiently heating a suitable medium which may be employed either for heating or power purposes; the apparatus being also adapted for refrigeration purposes.

My improved apparatus is so constructed that the medium to be heated is caused to flow in counter direction to the hot flue gases and wherein the flue gases are not permitted direct contact with the tubes or elements through which the medium to be heated is made to flow.

The invention also contemplates the provision of an apparatus wherein a heat exchange medium of high boiling point,—namely which will boil only at predetermined high temperatures, such as oil, soft metal and the like,—is employed for transferring the heat from the flue tubes or passages to the medium conveying tubes or coils of the apparatus.

Another object of my invention is the provision of apparatus in the nature of a heater or housing adapted for the evaporation of a refrigerant through certain of the passages or tubes; or whereby a refrigerant in the nature of a gas may be heated and employed for power purposes to operate a prime mover.

The apparatus is also so designed that a liquid refrigerant may be expanded through certain passages of the apparatus or housing for the purpose of refrigerating the housing of the apparatus which is so constructed that air, for example, may be led or made to pass through the chamber proper of the housing of the apparatus in direct contact with the refrigerating elements or refrigerant containing passages or tubes; or the air may be made to pass through a proper fluid or water for moistening purposes in advance of its discharge from the apparatus or housing.

Another object of the invention is the provision of a boiler shell or housing which is especially adapted for utilizing waste heat, such as flue gases from an existing plant; and provided with means whereby additional mediums, such as hot liquid and vapors, may also be directed through the boiler or housing in addition to the flue gases; while additional heat may be provided through the medium of the fire-box of the boiler.

The apparatus involves controllable means whereby the boiler or housing may be made to quickly function as a refrigeration apparatus; the housing being so constructed that the

medium to be heated is made to flow in counter direction to the flow of the flue gases when employed as a heater or boiler; and when used as a refrigerator the medium to be cooled is made to flow in counter direction to the expanded refrigerant passing through certain passages or tubes in the housing.

The apparatus is so designed that two mediums introduced into separate passages or portions of the housing may be heated at one and the same time, under different pressures, and both mediums made to flow in counter direction to the flow of the flue gases; one of said passages involving a controllable superheater path whereby one of the mediums may be superheated in its passage through the apparatus.

The housing or boiler is so constructed that one of the mediums to be heated is brought into direct contact with the flue passages or hot gas tubes, while the other medium is heated by transference of heat from the hot gas tubes through the first mentioned medium.

The apparatus is especially adapted for high pressure work as the refrigerant may be heated to a high temperature and high pressure to adapt it more particularly for power purposes, as the apparatus or housing is so constructed that a heat exchange medium of high boiling point can be then employed in the housing or boiler and the tubes or passages containing the refrigerant submerged or embedded in said heat exchange medium and a more uniform transference of heat thereby induced.

The apparatus is also designed that when it is employed for refrigeration or air conditioning or cooling, air may be introduced into the flue passages of the apparatus; while at the same time a fluid or fluids may be introduced into the chamber of the housing to serve as a heat exchange medium and also to be circulated through the chamber and employed for other purposes.

The apparatus or boiler is also so designed that loss of the heat exchange medium will be prevented and in the event the heat exchange medium should vaporize at the forward or hotter end of the boiler, this vapor will be conducted to the rear or cooler end of the boiler, the vapor being allowed to condense; the vapor conveying conduit being preferably so arranged that the hot vapor will flow by gravity to the rear and cooler end of the apparatus.

The above enumerated objects and purposes, as well as other objects and advantages inherent in the apparatus, will all be more fully

comprehended from the following detailed description of the accompanying drawings, wherein—

Figure 1 is a partial side and sectional elevation of my improved apparatus with portions broken away and shown in section.

Figure 2 is a vertical sectional view taken on the offset line 2—2 of Figure 1, looking in the direction of the arrows.

10 Figure 3 is a sectional elevation of my improved apparatus shown in connection with a closed refrigeration cycle.

15 Figure 4 is a top plan view with portions of the top of the housing or heater broken away to show internal construction.

The subject matter of this application is a part of my copending application and covers matter taken from said application Serial No. 602,863, filed April 2nd, 1932.

20 My invention, as exemplified in the drawings, involves a suitable insulated shell or housing 18, the bottom of which is provided with a suitable fire-box 11 which is preferably arranged forward of the front wall of the housing or boiler,

25 The fire-box is provided with a flue extension or chamber 11a which preferably extends throughout the length of the boiler or housing as shown in Figure 3. This flue extension 11a is provided at suitable prearranged points preferably with controllable dampers 12, 12 spaced apart, as more particularly shown in Figure 3, for the purpose of controlling the direction of flow or path of the hot gases of combustion as will hereinafter be described. Where a solid

30 fuel, such as coal or the like is employed, the fire-box is, of course, provided with the usual grate-bar, as at 13, and an ash-pit 14 provided therebeneath. The boiler housing or heater 18 is shown provided with a plurality of flues or

35 hot gas tubes 15 disposed vertically, their ends secured in the main top and bottom walls of the boiler or housing and with the lower ends of the tubes communicating with the flue chamber 11a of the fire-box 11. The flues or tubes 40 15 are preferably arranged equidistances apart and in parallel rows, as more clearly shown in Figure 4; with the upper ends of the flue tubes 15 communicating with the dome chambers 16 which are shown extending transversely of the

45 apparatus, each dome chamber 16 having communication with a certain number of the gas tubes 15.

These dome chambers 16 are shown preferably 50 provided with cover members 17 which may be hingedly connected as at 18 so that proper access to the gas or flue tubes 15 for cleaning purposes may be had. As is apparent from the

55 construction shown, the hot gases or products of combustion from the fire-box 11 (provided the first damper 12 is closed) are made to pass upwardly through the tubes 15 which are disposed in a vertical plane forward of the first damper 12, and discharged into the forepart of the first chamber 16. These gases are then

60 conveyed downwardly through the gas or flue tubes 15 of that same set, but which are disposed in a vertical plane immediately rearward of the first damper 12, and discharged into the extended flue chamber 11a beneath the bottom

65 wall of the housing or boiler and then caused to flow upwardly through the set of tubes 15 arranged forward of the second damper 12, discharging the hot gases into the second dome chamber 16, from whence the gases will flow 70 downwardly through those flue tubes 15 which

communicate with the flue chamber or extension 11a rearwardly of the second damper 12. These gases are then taken from this portion of the extended flue chamber 11a and conveyed upwardly through the set of tubes 15 at the rear end of the boiler which communicates with the last chamber 16 at the rear end of the boiler or apparatus; said chamber being provided with a suitable outlet.

10 The outlet of this chamber 16 is shown preferably provided with a suitable exhaust or blower at 19 for inducing proper draft or flow of the flue gases throughout the flue tubes in the manner heretofore described; the withdrawn flue gases then being conveyed to a suitable 15 smoke stack.

The flue extension 11a of the fire-box 11, preferably forward of the first damper 12, is provided with an inlet conduit, a portion whereof is shown at 20 in Figures 1 and 3, for the purpose of introducing hot flue gases from an existing plant. This conduit 20 is preferably provided with a damper or valve as at 21 so that passage therethrough may be controlled or shut off. This conduit 20 permits of the use of hot flue gases from any other source to be employed either separately or in conjunction with the hot gases from the fire-box 11, if the latter is in operation; the gases introduced by conduit 20 being made to flow in the circuitous or up and down manner heretofore described and the heat of the hot gases entirely utilized for heating the medium in the main chamber of the housing or boiler. The conduit 20 may also be employed for introducing air from a suitable source when the apparatus is employed for refrigeration or air conditioning work; the air being made to flow upwardly through the flues or passages 15; the cooled air being withdrawn by the exhaust or blower 19 and conveyed by a suitable conduit to the point of use.

The housing or boiler 18 is also provided with a plurality of horizontally disposed tubes 22, which are shown preferably extending through the front and rear walls of the boiler, with the inlet ends of the tubes 22 connected with the vertically disposed headers or manifolds 23; while the outlet ends of the tubes 22 are connected with headers or manifolds 24.

The tubes 22 are arranged in vertical series 50 between the flue tubes 15, as more clearly shown in Figure 2, with the ends connected with the manifolds or headers 23 and 24 which are arranged in the same vertical plane. That is to say, the apparatus is provided with headers or 55 manifolds 23 and 24 in number equal to the different vertical rows of tubes 22, as more clearly shown in Figure 4; and the respective manifolds or headers 23 are all connected to each other by short tubes or nipples as indicated at 25; the respective manifolds or headers 24 being also connected to each other by similar tubes or nipples 25. The inlet headers or manifolds 23 have communication with a conduit or pipe 26 which is provided with an expansion valve at 27. The pipe or conduit 26 is shown connected with the top chamber of a suitable refrigerant condenser 28. The conduit or pipe 26 is also shown provided with a conduit 29 provided with a valve as at 30. The conduit 29 is intended to convey any suitable refrigerant from an existing refrigerator, or a fluid medium, into the respective headers or manifolds 23, at which time valve 27 of conduit 26 is closed.

The outlet manifolds or headers 24 communicate with a pipe or conduit 31 which has a control valve 32 shown preferably disposed between the laterally disposed pipes 33 and 33^a which constitute, respectively, the ingoing and outcoming legs or portions of a superheater coil 33^b arranged in the upper and forward part of the boiler, and within the first dome chamber 16, see Figure 4, where the flue or heating gases are at a proper heating temperature.

It will be understood, of course, that the superheater may be placed adjacent the bottom of the boiler when it is intended merely to use waste gases from an existing plant and coming in through conduit 28; and it will also be understood that the superheater may have any desired and sufficient number of coils. Where the boiler is used for refrigeration or air conditioning purposes only, there will be no need for the superheater, in which case valves 34 and 35 in the inlet and outlet ends 33 and 33^a of the superheater will be closed. On the other hand, with the valve 32 arranged as shown, it is apparent that all the fluid coming from the manifolds or headers 24 into conduit 31 will be made to pass through the superheater when valve 32 is closed.

The front end of the boiler or apparatus is shown provided with a conduit 36 (see Figure 2) which preferably communicates with the lower part of the main chamber in the housing. The conduit 36 is shown provided with suitable valves at 37 and 38; and between these valves it is also provided with laterally disposed pipes 39 and 40 each of which has a valve at 41 and 42, respectively. Conduit 36 may be employed for introducing a fluid, as for example water or oil, into the main chamber of the boiler. At such times, valves 41 and 42 are to be closed, while valves 37 and 38 are opened.

Conduit 39 is more especially intended for the introduction of air into the main chamber of the boiler when the apparatus is to be used for air conditioning purposes; at which time, of course, the main chamber of the boiler 10 may be provided with a sufficient quantity of water through which the air will be made to percolate or filter.

After the desired quantity of water has been introduced, valve 38 is closed, valve 37 opened and valve 41 in air line 39 is then opened, while valve 42 in line 40 remains closed. Pipe 39 may connect with any suitable source of air supply and preferably extends upwardly into a plane above the water level in the boiler or housing 10.

Pipe 40 may communicate with any suitable source of vapor or waste steam which can be introduced through pipe 36 upon proper operation of the respective valves. With the pipe or conduit and valve arrangement shown, steam or any other suitable hot vapor or fluid can be introduced into the main chamber of the boiler, for use as a heat exchange medium for heating the fluid passing through tubes 22. If further heat is desired or necessary, the flue gases from an existing plant may be introduced through conduit 28 as previously described.

The opposite end of the heater housing or boiler shell, as at 43, is provided with an outlet conduit communicating with the main chamber and provided with a suitable valve 44, see Figures 3 and 4, whereby the conditioned air, for example, may be conveyed to any desired point of use; or the fluid or vapor which has been

introduced through conduit 36 may be conveyed to any other suitable point of use.

The boiler shell or housing 10, on one of its sides, is shown provided with a pipe 45, which preferably communicates at one end with the upper forward part of the main chamber of the boiler, while the opposite end is shown connected with the main chamber of the boiler preferably at the lower rear end thereof, see Figure 1. The pipe 45 is provided with suitable valves as at 46, 46. With the pipe arranged as shown, it is apparent that a portion of any vapor or steam that may be formed in the main chamber may pass into said pipe where the vapor or steam will condense and the cooled portion of the condensate returned to the coolest end of the boiler.

The purpose of intermediate valve 46 is to permit take-off or return at a point between the top and the rear bottom of the boiler; and especially where the boiler is only half full of liquid. With the pipe 45 connected with the forward upper part of the boiler, even though the boiler is full, steam forms on top, the turbulence of the liquid when boiling induces a slight circulation in the pipe 45 thereby increasing heat transfer in the boiler, while the steam entering the upper end of the conduit will condense and be transferred back into the boiler either at the center or intermediate part or at the bottom coolest part, or at both points.

The apparatus or boiler, at suitable points, may be provided with fluid level indicating gauges, as at 47, 47; and with suitable pressure gauges as at 48, as well as with suitable temperature indicating elements or thermometers as at 49.

The housing or boiler, at a suitable point, is provided with a drain pipe 50 having a suitable valve 51 to permit draining of the main chamber of the boiler, see Figure 3.

In Figure 3 I show my improved apparatus in conjunction with a closed refrigeration cycle involving a condenser as at 28.

The bottom or inlet chamber of the condenser 28 connects with a conduit 52 which communicates with a suitable compressor 53, while the latter at its inlet end communicates with a suction or exhaust line 54, which, in turn, has connection with the outlet pipe 31 50 coming from the headers or manifolds 24, as heretofore described, thus providing a closed refrigerating cycle through the apparatus.

Where the apparatus or boiler is intended for heating a medium passing through pipes 22, for example oil, air or other liquid, which would be introduced into pipes 22 by pipe 29, a take-off pipe 55 is provided, having a suitable valve 56. In such instance communication with the suction or exhaust line 54 is shut off by means of a valve as at 57.

Where the apparatus is intended for air conditioning purposes, the main chamber of the boiler or housing 10 is provided with a suitable liquid or water, for example to a level as indicated at a in Figure 3.

The air introduced under pressure through pipe 39, upon opening valve 41 and closing valve 38, is made to pass through the water and in contact with the tubes 22 which now are functioning as refrigerating tubes by circulating a suitable refrigerant from condenser 28 through the tubes 22; while the conditioned air is then taken off by conduit 43 upon opening valve 44, to be conveyed to the place of use.

Where the apparatus is intended for heating or power purposes, the main chamber of the boiler housing or shell is provided with a suitable heat exchange medium for transferring heat from the flue tubes 15 to the fluid containing tubes 22, as illustrated, for example, in Figure 1, where the main chamber of the boiler shell or housing is shown filled with a suitable medium at *b*. The medium, which is to be heated 5 in tubes 22, is introduced through conduit 29 upon opening valve 30 and closing valve 27, allowing the medium or fluid to enter the respective headers 23 and to flow through tubes 22 in counter direction to the passage of the flue 10 gases through tubes 15. The heated medium or fluid is taken off from the respective headers 24 by conduit 31 connected with conveying line 55 provided with valve 56. When desired or found necessary, the heated medium coming from the 15 outlet headers or manifolds 24 may first be made to pass through the superheater 33-33a-33b, the return leg or end 33a of the superheater communicating with conduit 31 beyond valve 32, which latter must be closed in 20 order to induce all of the fluid to pass through the superheater.

From the construction shown and described, it is also apparent that two mediums may be heated at one and the same time for separate 30 uses, if desired, and both mediums made to flow in counter direction to the flow of the flue gases.

Where this is desired, a fluid may be introduced through conduit 43 into the rear end of 35 the main chamber of the boiler housing and taken off, for example through conduit 36, or through a valve controlled outlet 58 adjacent the upper forward end of the boiler. It is also apparent that with my improved boiler the two 40 fluids may be heated under different pressures and to different temperatures. For example a fluid may be forced through tubes 22 by means of pipe 29, under high pressure, and heated by the medium in the housing and then superheated 45 in superheater tubes 33b, thus providing a fluid under high pressure and higher temperature than the medium in the main chamber.

As is apparent from the drawings and the description herein, the apparatus may be quickly converted from a refrigerating apparatus into a heating and power apparatus through the operation of valve mechanisms controllable at the will of the operator and this apparatus and its various methods of operation have been described in terms employed for purposes of description and not as terms of limitation, as modifications are possible and may be made without, however, departing from the spirit of my invention.

60 What I claim is:

1. In apparatus of the character described, a boiler or heater provided with a fire-box having a flue portion disposed from front to rear of the boiler at the bottom thereof; means 65 whereby the flue portion is separated into a plurality of flue chambers; the upper part of the boiler being provided with a plurality of flue-gas chambers; a plurality of vertically arranged flue tubes disposed intermediate of said flue portion and said flue-gas chambers; a plurality of horizontal medium conveying tubes arranged in vertical series intermediate of the vertically disposed flue tubes; manifold means at the inlet ends and at the outlet ends of said medium 70 conveying tubes; and valve controlled means 75

whereby a heat exchange medium may be introduced into the chamber of the boiler or heater into contact with all of said tubes.

2. In apparatus of the character described, a boiler or heater provided with a fire-box having a flue portion disposed from front to rear beneath the bottom of the boiler; controllable means whereby the flue portion may be separated into a plurality of flue chambers; a plurality of flue-gas chambers at the top of the boiler; a plurality of vertically arranged flue tubes intermediate of said flue portion and said flue-gas chambers whereby the flue gases are made to travel in a plurality of up and down passageways intermediate of the front and rear of the boiler or heater; flue gas take-off means at the rear of the boiler or heater; a plurality of horizontal tubes arranged intermediate of the vertical flue tubes; inlet means common to all of said horizontal tubes; outlet means common to all of said horizontal tubes; and valve controlled means whereby a heat exchange medium may be introduced into the main chamber of the boiler or heater into contact with and to surround all of said tubes.

3. In apparatus of the character described, a boiler or heater provided with a fire-box having a flue portion beneath the bottom of the boiler; means whereby the flue portion is separated into a plurality of flue chambers; a plurality of flue-gas chambers arranged at the top of the boiler or heater; a plurality of vertically arranged flue tubes disposed between said flue portion and said flue-gas chambers; a plurality of horizontally arranged tubes intermediate of the side walls of the boiler or heater and intermediate of the vertical flue tubes; inlet means common to all of said horizontal tubes; outlet means common to all of said horizontal tubes; superheater means arranged in one of said flue-gas chambers and having communication with said common means at the outlet ends of said horizontal tubes and having a valve controlled discharge outlet; and valve controlled means whereby a heat exchange medium may be introduced into the main chamber of the boiler or heater into contract with and to surround all of said tubes.

4. In apparatus of the character described, a boiler or heater provided with a fire-box having a flue portion beneath the bottom of the boiler; means whereby the flue portion is separated into a plurality of flue chambers; a plurality of flue-gas chambers at the top of the boiler; a plurality of vertically arranged flue tubes disposed between the flue chambers beneath the boiler and the flue gas chambers at the top of the boiler whereby the flue gases are made to flow in up and down directions from front to rear of the boiler; a plurality of horizontally disposed tubes arranged in vertical rows between the flue gas tubes; headers secured to the inlet ends of the horizontal tubes; headers secured to the outlet ends of said tubes; means whereby a fluid medium may be circulated through the main chamber of the boiler in contact with all of said tubes; and means whereby hot vapor from the main chamber may be condensed and returned to said chamber.

5. In apparatus of the character described, a boiler or heater provided with a plurality of vertically disposed flue tubes extending from bottom to top of the boiler; a plurality of horizontally disposed fluid conveying tubes arranged intermediate of said flue tubes, inlet means for introducing a fluid medium into all of said sec- 75

ond mentioned tubes; outlet means common to said second mentioned tubes for receiving the fluid medium therefrom; means whereby a heat exchange medium may be introduced into the 5 main chamber of said boiler or heater for transferring heat from the first mentioned tubes to the second mentioned tubes; and means whereby hot flue gases from an extraneous source may be conveyed to said flue tubes.

10. 6. In apparatus of the character described, a boiler or heater provided with a plurality of vertically disposed flue tubes extending from bottom to top of the boiler or heater; means whereby communication between the adjacent ends of 15 certain of said tubes is established so as to induce the hot gases to flow upwardly and downwardly in different sets of said tubes; means for introducing hot gases into the lower ends of the initial set of said flue tubes; gas take-off means 20 communicating with the last set of said tubes and for inducing flow of said gases through all of said tubes; a plurality of horizontally disposed tubes arranged intermediate of the first mentioned tubes; valve controlled means at the 25 inlet and at the outlet ends of the second mentioned tubes; and controllable means whereby a heat exchange medium may be introduced into the main chamber of said boiler or heater and in contact with all of said tubes.

30. 7. In apparatus of the character described, a housing; heating flues extending upwardly through the chamber of the housing; means disposed beneath said housing for supplying hot flue gases to said heating flues; means whereby 35 the hot gases are made to travel through the flues in opposite directions; evaporating tubes extending through the chamber of said housing intermediate and transversely of the first mentioned flues; means for introducing a fluid mentioned into the chamber of the housing in contact with the flues and tubes, and means including an exhaust fan for withdrawing gases from the heating flues.

40. 8. In apparatus of the character described, a housing forming a chamber, evaporating tubes extending through said chamber; heating flues extending through said chamber; means for supplying hot flue gases to said heating flues, supplemental means available at will for supplying 45 additional gases to said heating flues; means for introducing a fluid into said chamber; means for withdrawing the contents of said chamber; and means including an exhaust fan for withdrawing gases from said heating flues.

50. 9. In apparatus of the character described, a housing forming a chamber; evaporating tubes extending through said chamber; heating flues extending through said chamber; means for supplying heated gases to said flues; supplemental means available at will for supplying 55 additional gases to said heating flues; means for introducing a heat exchange medium into the chamber of said housing; and means including an exhaust fan for withdrawing gases from said heating flues.

60. 10. In apparatus of the character described, a housing forming a chamber; a plurality of vertically disposed flue tubes between the bottom and top walls of the chamber; means whereby said flue tubes are arranged in sets relative to the passage of the flue gases therethrough; means for supplying hot flue gases at the lower ends of the initial set of said tubes; means including an exhaust fan communicating 65 with the outlet ends of the final set of said

tubes; a plurality of horizontally disposed tubes in said chamber intermediate of the first mentioned tubes; means common to the inlet ends of said second mentioned tubes for introducing a fluid medium; valve controlled means common to the outlet ends of said second mentioned tubes for receiving the fluid medium therefrom; superheater means arranged in the path of the hot flue gases and communicating with said means common to the outlet ends of the second 10 mentioned tubes; and means whereby a heat exchange medium may be introduced into the chamber of the housing to surround all of said tubes.

11. In apparatus of the character described, 15 a housing forming a chamber; a plurality of tubes arranged vertically between the top and bottom walls of the housing; means whereby hot flue gases may be introduced into said tubes; take-off means communicating with the 20 discharge ends of the tubes; a plurality of horizontally disposed tubes arranged intermediate of the vertical rows of the first mentioned tubes; valve controlled means common to the inlet 25 ends of the second mentioned tubes; valve controlled means common to the outlet ends of said second mentioned tubes; means for introducing a fluid medium into the chamber of said housing; and means whereby steam or vapor formed in the upper part of the hottest portion of said 30 chamber may be condensed and returned to the lower part of a cooler portion of said chamber.

12. In apparatus of the character described, 35 a housing forming a chamber; means whereby a fluid or fluids may be introduced into said chamber to be heated or refrigerated; a plurality of vertically arranged tubes; means whereby hot flue gases may be introduced into said tubes; take-off means communicating with 40 the discharge ends of said tubes; refrigerating elements disposed between the vertical tubes, compressor means connected to the discharge of said elements, condenser means and expansion means connected with the inlets of said refrigerating elements to form a closed refrigeration 45 system; and valve means including the expansion means whereby the elements may be disconnected from the compressor and condenser and the apparatus function as a heater or 50 boiler.

13. In apparatus of the character described, a housing or shell; chambers arranged at the top and a flue at the bottom of said housing or shell; a plurality of tubes arranged vertically 55 in the housing or shell in communication with said chambers and flue; means whereby a heating medium may be introduced into said flue; means whereby the flue may be divided into chambers and the direction of flow through said 60 chambers and tubes may be controlled; take-off means for withdrawing the heating medium; a plurality of tubes arranged horizontally intermediate of the vertical tubes; inlet means common to the last mentioned tubes whereby a 65 fluid or gas may be introduced into all of said tubes; outlet means common to said last mentioned tubes for receiving the fluid or gas therefrom; valve controlled connections communicating with the main chamber of the housing 70 or shell whereby a fluid or fluids may be introduced into said chamber to surround the tubes; in combination with refrigerating apparatus; and valved arrangements communicating with the inlet means and with the outlet means of 75

said horizontal tubes whereby said apparatus may be employed for heating and power purposes or for refrigeration purposes.

14. In apparatus of the character described, 5 a housing forming a chamber; chambers arranged at the top and a flue at the bottom of said housing; a plurality of vertically arranged tubes for establishing communication between said chambers and flue; means whereby hot flue 10 gases may be introduced into said flue; controllable means whereby the flue may be divided into chambers and the direction of flow of said hot gases may be controlled; take-off means for said flue gases; a plurality of tubes disposed 15 horizontally intermediate of the first mentioned tubes; inlet means common to the last mentioned tubes whereby a fluid or gas may be introduced into all of said tubes; outlet means common to said last mentioned tubes for receiving the fluid or gas therefrom; valve controlled connections communicating with the main chamber of the housing whereby a fluid or 20 fluids, may be introduced into said chamber and in contact with said tubes; and controllable 25 take-off means whereby the fluid or fluids may be withdrawn from said chamber.

15. In apparatus of the character described a housing forming a chamber; heating flues extending through the chamber of the housing; 30 means for separately supplying hot gases or air to be cooled to said flues; fluid conveying tubes extending through the chamber intermediate of the flues; inlet means common to the ends of said tubes for supplying all of said tubes; outlet 35 means common to the other ends of the tubes; and means whereby a fluid medium may be introduced into the chamber in contact with the flues and tubes.

16. In apparatus of the character described, a 40 housing provided with hot gas conveying passages and with fluid conveying passages; means for supplying hot gases to said first mentioned passages; expansion means and separately controlled fluid introducing means connected with the 45 inlets of said fluid conveying passages; valve controlled discharge lines connected with the outlets of said fluid conveying passages; and means whereby a fluid medium may be introduced into the housing in contact with both 50 mentioned passages and withdrawn from said housing.

17. In apparatus of the character described, a housing provided with hot gas conveying passages and with fluid conveying passages extending 55 entirely through the housing and arranged intermediate and criss-cross of the first passages, whereby said passages may be surrounded by a heat exchange medium, means for supplying hot gases to said first mentioned passages, means for withdrawing the gases from said passages, controllable means for separately introducing a medium to be heated or a refrigerant medium into the second mentioned passages so as to flow 60 in counter direction to said gases, means for withdrawing the medium from the second mentioned passages, and means hereby said heat exchange medium may be circulated through said housing.

18. In apparatus of the character described, 70 a housing provided with hot gas conveying passages and with fluid conveying passages, whereby said passages may be surrounded by a heat exchange medium, means for supplying hot gases to said first mentioned passages, means for withdrawing the hot gases from said passages,

means for introducing a medium to be heated into the second mentioned passages so as to flow in counter direction to said hot gases, super-heater means arranged in the path of the hot flue gases and communicating with the fluid conveying passages, and means for withdrawing the fluid from the second mentioned passages.

19. In apparatus of the character described, a combined heating and refrigerating unit comprising a shell or housing; heating passages disposed vertically through the shell or housing; means for supplying hot gases to said passages; means whereby the direction of flow of the gases through the passages may be controlled; refrigerant evaporating passages disposed through the 15 shell or housing intermediate and transversely of the heating passages; controllable means whereby a different medium may be introduced into the second mentioned passages; means for introducing a medium into the housing to be 20 heated or refrigerated; controllable means whereby air to be cooled may be introduced into the first mentioned passages; and means for withdrawing said medium from the housing.

20. In apparatus of the character described, 25 a combined heating and refrigerating unit comprising a shell or housing; heating passages disposed through the shell or housing; means for supplying hot flue gases to said passages; refrigerant evaporating passages disposed through the 30 shell or housing intermediate of the heating passages; means whereby different mediums may be introduced into the shell or housing, in intimate relation with each other and into contact with said passages, whereby the mediums may 35 be heated or refrigerated; and means for withdrawing said mediums, either singly or jointly.

21. In apparatus of the character described, a combined heating and refrigerating unit comprising a shell or housing; flue gas passages disposed through the shell or housing; means for supplying hot flue gases to said passages; controllable means whereby air to be cooled may be applied to said passages; other passages disposed through the shell or housing intermediate 45 of the flue gas passages; controllable super-heater means arranged in the gas passages and communicating with the discharge ends of said other passages; arrangements whereby a refrigerant or a medium to be heated may be made 50 to pass through said second mentioned passages; and controllable means whereby the refrigerant or heated medium may be withdrawn from said passages.

22. In apparatus of the character described, a 55 combined heating and refrigerating unit comprising a shell or housing adapted to be provided with a heat exchange medium; passages disposed through the shell or housing; means whereby hot flue gases or air to be cooled may 60 be supplied to said passages; means whereby the direction of flow through said passages may be controlled; other passages disposed through the shell or housing intermediate of the first mentioned passages; means whereby different refrigerants may be introduced into the second 65 mentioned passages; means for withdrawing the gases or air from the first mentioned passages; and means whereby the refrigerant may be withdrawn from the second mentioned passages.

23. In apparatus of the character described, a 70 housing forming a chamber; valve controlled means communicating with said chamber whereby a fluid or fluids may be circulated through said chamber; a plurality of passages disposed 75

through the chamber; valve controlled means whereby a refrigerant or other medium may be circulated through said passages, a plurality of flues disposed through the chamber intermediate 5 of the passages; and means whereby hot gases or air may be separately introduced into said flues.

24. In apparatus of the character described, a housing forming a chamber; refrigerating means 10 for refrigerating said chamber; valved means whereby a fluid or fluids may be introduced into said chamber; independent valved means whereby moisture may be separately withdrawn from said chamber while the first mentioned valved 15 means is in operation, and means whereby a heating medium may be conveyed through said chamber.

25. In apparatus of the character described, a shell or housing adapted to receive a medium to 20 be heated and provided with hot gas passage or passages, heat generating means provided with a flue disposed beneath the shell or housing and communicating with said passage or passages, and means whereby hot gases from a separate 25 source may be conveyed into said flue beyond the point of communication of the flue with said first means whereby the hot gases from the first mentioned means and the second mentioned means may be commingled before introduction 30 into the first mentioned passage or passages; said heat generating means and the last men-

tioned means being adapted to be separately or jointly utilized, and means for conveying the medium to be heated to and from said shell or housing.

26. In apparatus of the character described, a 5 housing forming a chamber and provided with a hot gas or air receiving flue therebeneath, valve controlled means communicating with said chamber whereby a medium may be circulated through said chamber; a plurality of passages 10 disposed through the chamber and communicating with said flue; controllable means whereby the direction of flow of the gas or air may be regulated; other passages disposed through the chamber intermediate of the first mentioned 15 passages; and means whereby another medium may be introduced into and withdrawn from said last mentioned passages.

27. In apparatus of the character described, a shell or housing forming a chamber, valve controlled means communicating with said chamber whereby a medium may be circulated through said chamber; a plurality of passages disposed 20 through the chamber; controllable means whereby circulation through some or all of said passages 25 may be controlled; other passages disposed through the chamber intermediate of the first mentioned passages; and means whereby another medium may be introduced into and withdrawn from said last mentioned passages. 30

AUGUST SCHWARZ.
